UNITED STATES PATENT OFFICE.

GODFREY SMITH, OF CANAL DOVER, OHIO.

POLISHING-MACHINE.

No. 870,056.

Specification of Letters Patent.

Patented Nov. 5, 1907.

Application filed March 30, 1907. Serial No. 365,577.

To all whom it may concern:

Be it known that I, GODFREY SMITH, a citizen of the United States, residing at Canal Dover, in the county of Tuscarawas and State of Ohio, have invented certain new and useful Improvements in Polishing-Machines, of which the following is a specification, reference being had therein to the accompanying drawing.

My invention relates to improvements in machines for grinding, polishing and buffing sad irons or other articles.

The principal object of the invention is to provide a machine of this character upon which a plurality of irons or the like may be simultaneously polished and each one successively polished upon several of its faces without removing it from its holding device in the machine.

Further objects and advantages of the invention, as well as the structural features by means of which these objects are attained, will be made clear by an examination of the following specification, taken in connection with the accompanying drawings, in which

Figure 1 is a top plan view of one embodiment of my invention; Fig. 2 is a detail transverse sectional view through the same; Fig. 3 is a diagrammatic view 25 representing the periphery of the work carrier frame or wheel straightened out into the same plane and showing the arrangement of the trip devices for actuating the mechanisms that operate the chucks to present different portions of the sad irons to the polishing 30 wheels; Fig. 4 is a top plan view of one of the work chucks, its support and a portion of the carrier frame or wheel; Fig. 5 is a vertical section taken on the plane indicated by the line 5—5 in Fig. 6; Figs. 6 and 7 are vertical sections taken on the planes indicated by the 35 lines 6—6 and 7—7 in Fig. 5; Fig. 8 is a perspective view of the sliding jaw of one of the work chucks; Figs. 9 and 10 are respectively longitudinal and transverse sections through one of the chucks; Fig. 11 is a side elevation of one of the polishing wheels, its support 40 and driving mechanism; Fig. 12 is a perspective view of one of the stationary trips; Fig. 13 is a similar view of one of the stationary racks; and Figs. 14 and 15 are respectively end and side views of one of the chuck supports.

45 The preferred embodiment of my invention illustrated in the drawings, consists of a continuously rotating work carrier 1 preferably in the form of a wheel like frame mounted preferably upon a vertical pivot and provided around its outer edge or rim with a plurality 50 of work holding chucks 2 so mounted in supports 3 that they may be moved or swung in different directions to present different faces of the sad irons or other work and different portions of said faces to a plurality of polishing wheels 4 mounted on stationary supports 5 arranged around the work carrier at suitable inter-

vals. The carrier frame 1, as here shown, comprises a hub 6 rotatable upon a suitable pivot bearing 7 secured to the floor or any support, and connected by radial spokes 8 to a double rim consisting of inner and outer annular members preferably in the form of I-beams 60 suitably connected and spaced apart. The work carrier 1 is adapted to be continuously rotated and it is preferably driven by arranging upon the bottom of the outer rim 10 an annular series of gear teeth 11 which mesh with a pinion 12 arranged upon a horizontal 65 shaft 13 journaled in a bearing 14 secured to the floor and provided upon its outer end with a pulley 15 which may be connected by a belt or band to a suitable power shaft. In order to support the rim or outer portion of the work carrier, I preferably secure to the 70 spokes 8 an annular T-shaped rail 16 which is arranged concentric with the pivot 7 and is adapted to have its headed depending flange engage grooved supporting wheels 17 journaled in suitable bearings 18 upon the floor. Any number of the wheels 17 may be arranged 75 around the pivot 7 so that the rail 16 can run upon them to sustain the weight of the outer portion of the work carrier and relieve the spokes 8 from undue strain.

Each of the work chucks 2 comprises a substantially 80 rectangular body 19 having trunnions 20 at its opposite ends and a depending semi-circular flange 21 adjacent to one end. Upon the flat top of the body 19 is a stationary chuck jaw 22 and a sliding one 23. While these jaws may, within the scope of my invention, be varied as desired for the reception of articles of any description that are to be polished by the machine, the ones here shown are especially designed for the reception of a detachable handle sad iron and their opposing inner faces are curved to conform to the 85 curved sides of such an iron. The jaw 22 may be formed integral with the chuck body 19 upon one of its sides or it may be laterally adjustable thereon by means of bolts 24 passed through slots formed in it, or in any other suitable manner. The movable jaw 23 90 is provided upon its bottom with a sliding bar 25 which is beveled at its edges so that it is of dove-tail form in cross section and which is adapted to slide in a similar shaped transverse groove 26 formed in the top of the chuck body 19. The slide 25 slides freely in said 95 groove and it is actuated in one direction by a spring 26 so that the sliding jaw 23 will be held normally in its closed position. The spring 26 is here shown in the form of a coil seated in a recess in the top of the body 19 and having one of its ends bearing against a 100 stop pin or screw 27 carried by the slide 25, as will be readily seen upon reference to Figs. 4, 9 and 10. The slide 25 is of such length that its free or outer end projects beyond the outer side face of the chuck body 19 105 in order that it may be actuated by a cam lever 28 suit- 110

ably pivoted at 29 upon said side of the chuck. The cam 28 is so constructed that when it is actuated, as hereinafter described, it will move the slide 25 inwardly against the tension of the spring 26 to move 5 the jaw 23 away from the jaw 22 to release the iron, and when so actuated it will retain the slide and jaw 23 in their open positions until the outer end of the cam lever has been depressed. In order to effectively 10 retain the iron between the two jaws of the chuck, I preferably provide upon their inner faces studs or pins 30, 31 which are adapted to enter recesses or seats formed in the iron. As seen in Fig. 10, the pin 31 in the jaw 23 is slidably mounted and is pressed inwardly by a leaf spring 32. But, as above noted, the 15 chuck jaws may be of any other form and construction than here shown and described so as to adapt the chuck for holding an article of any size and shape.

The trunnions 20 of the chuck are journaled in bearings 33 upon the center of the sides of one of the supports 3. Each of the latter is in the form of an open frame consisting of end plates 34, 35 connected by lower side bars 36 and upper side bars 37, 38 upon which latter are arranged the bearings 33. Upon the end plates 34, 35 are provided trunnions 39 which are journaled 25 in bearings 40 arranged upon the tops of the two rims 9, 10 of the carrier frame. It will be noted upon reference to Fig. 4 that the chuck support 3 is arranged between the two rims with its trunnions 39 extending radially with respect to the carrier frame or wheel, 30 and that the chuck 2 is arranged within the support 3 with its trunnions disposed in a plane at right angles to that of the trunnions 39. This mounting of the chuck upon the carrier frame enables the work within it to be swung or tilted in any direction, the pivotal or 35 swinging movement of the chuck permitting it to swing inwardly and outwardly so that it may be turned over upon either side to cause either side face of the iron or work to be uppermost, and the pivotal or swinging movement of the chuck support permitting 40 it and also the chuck and the work therein to be swung or tilted so that different portions of said side faces of the iron or work or of the bottom or top face of the latter to be presented to a polishing wheel.

In order to lock the chuck in either its normal upper right position or when swung down upon either of its sides, I provide at suitable points in the depending flange 21 of the body 19, one or more recesses or seats 41 which are adapted to receive the upwardly bent end of a locking lever 42 which is pivoted intermediate its ends at 43 upon a depending portion of the cross bar 37. The opposite or free end of the lever 42 extends inwardly and is arranged in the path of an arm 44 on the upper end of a slide 45 mounted in a suitable guide 46 upon the inner end plate 34. The slide bar 45 carries at its lower end an inwardly extending pin 47 which projects through and slides in a vertical slot 48 formed in said plate 34. The pin 47, when the support 3 is in its normal upright position, is disposed directly above a vertically sliding bar 49 arranged in 50 guides 50 upon the inner rim 9, as clearly shown in Figs. 5 and 7. The lower end of the slide 49 has a slot and pin connection with a bell crank or lever 51 which is pivoted upon the rim 9 in a recess cut in its bottom flange. One arm of the lever 51 depends beneath the 60 bottom plane of the rims 9, 10 and is adapted to be

actuated by suitable trips arranged in its path upon the floor and at proper intervals, the preferred form of these trips being illustrated at 52 in Fig. 12. It will be observed that when the lever 51 is actuated by passing over one of the trips 52, the slide 49 will be elevated and the latter will, through its engagement with the pin 47, elevate the slide 45 and the latter in turn, through its arm 44, will swing the locking lever 42 to release it upon one of the seats 41 in the chuck body. 70

In order to swing the chuck over upon either of its sides and to return it to its upright position, after it has been unlocked by the mechanism just described, I provide upon one of the trunnions 20 a ratchet wheel 53 having four teeth which project downwardly, two 80 being arranged upon either side, as clearly shown in Figs. 5 and 6. The teeth 54 upon one side are adapted to be engaged by a resilient pawl 55 and the teeth 56 upon the other side are adapted to be engaged by a similar resilient pawl 57. These pawls 55, 57 are carried by the upper ends of vertical bars or rods 58 mounted for vertical sliding movement in one of the lower cross bars 36 and guides upon the upper cross bar 38. The lower ends of the rods 58 are adapted to lie above the free ends of cam shaped levers 59 which have 90 their other ends pivoted in a cross bar 60 connecting the rims 9, 10. The cam lever 59 for the pawl 55 is connected by a link to a bell crank or lever 61 and the cam lever 59 for the other pawl 57 is similarly connected by a link to a bell crank or lever 62. These levers are suitably pivoted in a cross bar 63 connecting the rims 9, 10 and have their free arms or ends depending beneath the plane of the bottom of the rims 9, 10 so as to be actuated by trips similar to the ones shown in Fig. 12. These trips are so arranged upon the floor beneath the 100 machine that the levers 61, 62 will be actuated to swing the chuck in the desired direction. When the lever 61 is actuated it will cause the pawl 55 to engage one of the teeth 54 and swing the chuck inwardly and over upon its inner side so as to turn the outer edge of the 105 iron between its jaws uppermost, and that when the other lever 62 is actuated, its pawl 57 will engage one of the teeth 56 to swing the chuck in the opposite direction, that is, outwardly. The pawls 55, 57 are resilient so that in returning to their normal positions, 110 they slip over the beveled upper edges of the ratchet teeth. Two teeth are provided upon each side of the wheel to enable the chuck to be turned from one of its sides over upon its opposite side, as will be readily understood upon reference to Fig. 5.

In order to swing the chuck support 3 for the purpose of presenting a curved surface of an iron or other work to one of the polishing wheels 4, as the chuck passes such wheel, I form upon the bottom edge of the outer end plate 35 a segmental worm gear 63 which meshes 120 with a worm 64 rotatably mounted in bearings 65 upon the outer rim 10 and provided upon one of its ends with a bevel gear that meshes with a similar gear fixed upon a vertical shaft 65 also journaled in bearings upon the rim 10, as clearly shown in Fig. 6. Upon the depending lower end of the shaft 65 is a toothed wheel or gear 66 which, as the work carrier frame is rotated, is adapted to mesh with stationary racks 67 arranged at suitable intervals upon the floor beneath the machine. The preferred construction of the racks 67 is shown in Fig. 130

13 but they may be of any other suitable form. Each one is of such length that the worm will be turned to the desired extent and certain of them are arranged to engage one side of the toothed wheel 66, while others 5 are arranged to engage opposite side of the same in order that the shaft 56 will be turned in opposite directions for the purpose of swinging the support 3 first in one direction and then in the opposite direction, as presently explained.

10 In order to automatically release the polished iron upon the chuck, I provide upon the end plate 35 of the support 3 a guide 80 in which is slidably mounted a slide bar 81, the upper end of which is so disposed that when elevated it will strike the outer end of the cam 15 lever 28 to actuate the same and move the sliding chuck jaw to its open position. The lower end of the bar 81 has an outwardly extending pin 82 which projects through and slides in a vertical slot 83 in the plate 35 and has its outer end arranged above a sliding bar 84 20 mounted in a guide upon the rim 10 and having its lower end connected by a slot and pin connection to a bell crank or lever 85 similar to the lever 51. When the lever 85 is actuated by a trip, such as the one shown in Fig. 12, the bar or slide 81 will be elevated to actuate 25 the cam lever 28.

Any number of the work chucks may be arranged around the carrier frame 1 and any number of the polishing wheels or equivalent devices may be employed so 30 that one or more faces or surfaces of the work will be properly ground or polished. As shown in Fig. 1, eight of the polishing wheels 4 are provided, the first four numbered 68 are comparatively broad and adapted to polish the flat bottom surfaces of the irons; the next two 69 are narrow and adapted to polish one of the side edges 35 of the iron and the last two 70 are similar and are adapted to polish the opposite side edges of the irons. As shown in Fig. 11, each of the polishing wheels (which may be of any form and construction) is fixed upon a shaft 71 journaled in suitable bearings upon the outer 40 end of a swinging arm 72 which has its bifurcated inner end pivoted upon a standard 5 rising from the floor. The arm 72 is held in an adjusted position so as to cause its polishing wheel to properly contact the irons, by a lever 74 pivoted upon the standard 5 and having one 45 of its ends connected by a link to said arm and its other end suitably locked by a well known form of pawl and rack locking mechanism 75. On the shaft 71 is a pulley 76 and upon the standard 5 are two pulleys 77, 78. A drive belt or band 79 from a suitable power shaft passes 50 around the pulleys 77, 76, 78, as shown in Fig. 11 for the purpose of rotating the polishing wheel.

The operation of the machine will be readily understood from the foregoing description taken in connection with Figs. 1 and 3 and the following brief statement. 55 The operator stands at the point *a* and, as the work carrier frame rotates, places unpolished irons in the chucks and removes the polished ones as they approach him. When he places an unpolished iron between the open jaws of one of the chucks, he swings the outer 60 end of the cam lever 28 downwardly so that the spring 26 moves the sliding chuck jaw to its closed position to clamp the iron in the chuck. As the carrier frame continues to rotate, the irons have their flat bottom surfaces polished by the four wheels 68 as they pass under 65 the same and as they leave the last wheel 68, one of the

trips 52 actuates the lever 51 to disengage the locking lever 42 from its central seat in the body of the chuck. Immediately after the unlocking of the chuck, another of the trips 52 actuates the lever 61 to swing the chuck inwardly upon its inner side so that the outer side edge 70 of the iron will be uppermost. When the chuck is in this position, shown at *b* in Fig. 1, the toothed wheel 66 meshes with one of the racks 67 so that the chuck and its iron will be swung forwardly or to the right to an angle of about 60°. When in this position, the iron 75 contacts the first of the polishing wheels 69 and, as it passes under the same, said toothed wheel 66 engages another and a longer one of the racks 67 which causes the iron to be swung to the left to an angle of about 60°, as indicated in Fig. 3. As the iron passes under the 80 second wheel 69, the toothed wheel 66 engages another of the racks 67 which restores the support 3 to its normal horizontal position. The lever 51 is then actuated by one of the trips 52 to again unlock the chuck body and immediately after it is unlocked, the lever 85 85 2 is actuated to restore the chuck to its upright position, shown at *c* in Fig. 1. Two other trips 52 then successively actuate the levers 51, 62 a second time to first unlock the chuck and then swing it outwardly and over upon its outer side so that the inner side edge of 90 the iron will be uppermost. When the iron is thus held upon its side, as at *d* in Fig. 1, the toothed wheel 66 passes between and engages a series of the racks 67 which causes the support 3 to be rocked first to the right, then to the left and then return to its normal position, as will be understood upon reference to Fig. 3. After the second side edge of the iron has been polished by passing under the wheels 70, in a manner similar to that in which its first mentioned side edge was polished in passing under the wheels 69, two of the trips 100 52 successively actuate the lever 51 and the lever 62 to unlock the chuck and then return it to its upright position, as shown at *e* in Fig. 1. When in the latter position, the iron is ready to be removed from the chuck and as it approaches the point *a*, one of the trips 52 actuates the lever 85 which causes the cam lever 28 on the chuck to be elevated and to force the sliding chuck jaw to its open position.

Having thus described my invention what I claim and desire to secure by Letters Patent is:—

1. The combination of a continuously rotating work carrier, work chucks thereon for holding said irons or other articles to be polished, a plurality of polishing wheels arranged around the carrier, and means for swinging said chucks to present different side faces of the irons or other work in them to said polishing wheels.

2. The combination of a continuously rotating work carrier, work chucks thereon for holding said irons or other articles to be polished, a plurality of polishing wheels arranged around the carrier, means for swinging said chucks to either side to present different faces of the irons or other work to certain of said polishing wheels, and means for swinging said chucks endwise to present different portions of said faces of the irons to said wheels.

3. The combination with a polishing wheel, of a rotary carrier frame, and a work chuck mounted upon said carrier frame for swinging movement in planes at angles to each other.

4. The combination with a polishing wheel, of a rotary carrier frame, a pivoted support upon said carrier frame and a work chuck pivotally mounted upon said support for movement in a plane at right angles to the movement of said support.

5. The combination with a polishing wheel, of a rotary carrier frame, a work chuck mounted for swinging movement upon said carrier frame means for locking the chuck against movement and means for unlocking the same. 65
5. 6. The combination with a polishing wheel, of a rotary carrier frame, a swinging work chuck upon said carrier frame and means for locking the chuck against movement. 70
7. The combination with a polishing wheel, of a rotary carrier frame, a pivoted support upon said carrier frame, 10 means for tilting said support, a swinging work chuck upon said support, and means for actuating said chuck. 75
8. The combination with a polishing wheel, of a rotary carrier frame, a movable support upon said carrier frame, means for actuating said support, a swinging work chuck 15 upon said support, means for actuating said chuck, and means for locking said chuck against movement. 80
9. The combination with a polishing wheel, of a rotary carrier frame, a pivotally mounted support upon said carrier frame, means for swinging said support upon 20 its pivot, a pivotally mounted work chuck upon said support and means for swinging said chuck upon its pivot. 85
10. The combination with a polishing wheel, of a rotary carrier frame, a pivotally mounted support upon said carrier frame, means for swinging said support upon its 25 pivot, a pivotally mounted work chuck upon said support, means for swinging said chuck upon its pivot and means for locking said chuck against movement. 90
11. The combination with a polishing wheel, of a rotary carrier frame, a swinging support upon said carrier frame, 30 worm gearing for actuating said support, a swinging work chuck upon said support, means for locking said chuck against movement, and a pawl and ratchet device for swinging said chuck upon its pivot. 95
12. The combination of a carrier frame, a support 35 thereon, a work chuck pivotally mounted on said support, a ratchet wheel carried by said chuck, a sliding pawl for actuating said ratchet wheel and a trip device for actuating said pawl. 100
13. The combination of a carrier frame, a support 40 pivotally mounted thereon and carrying a worm gear, a worm upon said carrier frame to mesh with said gear, a shaft geared to said worm, a toothed wheel upon said shaft, a stationary rack for engagement with said toothed wheel and a work chuck upon said support. 105
14. The combination of a carrier frame, a support 45 thereon, a chuck pivotally mounted upon said support and provided with seats, a locking lever to engage said seats, a slide bar for actuating said lever, a trip device for actuating said slide bar and means for swinging said chuck upon its pivot. 110
15. The combination of a carrier frame, a work chuck 50 mounted thereon and having a movable jaw, a cam lever for actuating said jaw, a sliding bar for actuating said cam lever and a trip device for actuating said sliding bar. 115
16. The combination of a carrier frame, a support 55 thereon, a work chuck upon said support and provided with a stationary jaw and a movable jaw, a slide carried by said movable jaw, a spring for actuating said slide in one direction, a cam lever for actuating said slide in the 60 opposite direction and means for actuating said cam lever. 120
17. The combination of a pivot bearing, a wheel like carrier frame having a hub to engage said bearing, a rim and radial spokes connecting said hub and rim, work chucks carried by said rim, rollers arranged around said pivot bearing and an annular rail secured to said spokes and engaged with said rollers. 125
18. The combination of a vertical pivot, a wheel like carrier frame disposed horizontally and rotatably mounted upon said pivot, means for rotating said carrier frame, 70 work chucks upon said carrier frame and a relatively stationary polishing wheel to engage the work in said chucks. 75
19. The combination of a vertical pivot, a wheel like carrier frame disposed horizontally and rotatably mounted upon said pivot, said carrier frame having spaced rim members, swinging supports arranged between said rim members, swinging work chucks upon said supports, means for operating said supports and means for operating said work chucks. 80
20. The combination of a rotatable carrier frame, swinging supports thereon, swinging chucks upon said supports, means for locking said chucks, means for actuating said chucks, means for actuating said supports and stationary devices for operating the chuck locking means, the chuck actuating means and the support actuating means. 85
21. In a machine for polishing sad irons or other articles, the combination with polishing means, of a carrier work holders upon said carriers, means for swinging said work holders to either side to present different faces of the irons or other work to said polishing means and means for swinging said work holders endwise to present different portions of the faces of the irons to said polishing means, substantially as described. 90
22. The combination with a polishing means of a carrier, a work chuck or holder pivoted on the carrier, a ratchet upon the chuck, a pawl for actuating the ratchet and means for actuating said pawl, substantially as described. 95
23. The combination with a polishing means, of a carrier, a work holding support pivoted upon the carrier, a worm gear upon said support, a worm upon the carrier to mesh with said gear, a shaft operatively connected to said worm, a toothed wheel upon said shaft and a stationary rack to actuate said toothed wheel, substantially as described. 100
24. The combination with a polishing means, of a carrier a pivoted work holder of the chuck upon the carrier, means for swinging said chuck, a locking member adapted to engage the chuck and hold it against movement in its different positions and means for actuating said locking member, substantially as described. 105
25. The combination with a polishing means, of a carrier, a work chuck thereon and having a stationary jaw and a movable jaw, a slide carried by the movable jaw, a spring for actuating said movable jaw to its closed position, a cam to engage the slide and operate the movable jaw to its open position and means for actuating said cam, substantially as described. 110
- In testimony whereof I hereunto affix my signature in presence of two witnesses.
- GODFREY SMITH.
